SHEET-FEEDING MECHANISM

Bruce Wale, Berkeley, Calif.

Application August 2, 1939, Serial No. 287,881

20 Claims.

(Cl. 271—26)

The invention relates to mechanism for consecutively feeding sheets from a pile of the type for delivery to printing presses or the like.

One object of the invention is to provide improved sheet-feeding mechanism which includes pneumatic devices for separating and fluffing several of the top sheets of a pile, co-ordinated suction means for lifting successive sheets in the path of the pneumatic means, and means for advancing the sheets in succession.

Another object of the invention is to provide improved feed mechanism which includes means for acting on the rear end portions of the sheets so that longer periods are available for the functioning of the feed mechanism than when the sheets are separated from the pile at their front ends.

Another object of the invention is to provide improved means for maintaining the top of the stack of sheets in a substantially constant relation to the feed mechanism.

Another object of the invention is to provide improved feed mechanism which includes means for readily timing the several pneumatic devices which act upon the sheets.

Another object of the invention is to provide feed mechanism which includes suction-means operating to lift successive sheets vertically and means in addition thereto for advancing the lifted sheets laterally to the press.

Another object of the invention is to provide improved sheet-feeding mechanism which is adapted to be readily adjusted for feeding sheets of different lengths and widths.

Other objects of the invention will appear from the detailed description.

The invention consists in the several novel features which are hereinafter set forth and are more particularly defined by claims at the conclusion hereof.

In the drawings:

Fig. 1 is an elevation of the operator's side of the machine embodying the invention, parts being shown in section.

Fig. 1^a is a detail of the ratchet device for intermittently advancing the belts for moving the sheets longitudinally.

Fig. 2 is an elevation of the side of the feed mechanism opposite the operator's side.

Fig. 2^a is a detail of the detent for controlling the operation of the pawl for lifting the sheet-supporting table.

Fig. 3 is a central longitudinal section.

Fig. 4 is a plan, parts being broken away for illustrative purposes.

The invention is exemplified in mechanism comprising a pair of frame-sides *c*, *c'*, in which are journaled a pair of co-acting upper and lower wheels *b*, *b'* for delivering the sheets from the mechanism to the press, as well understood in the art. A sprocket chain *p* driven from the press, drives a sprocket *p'*, which is fixed to the shaft *b'* of the lower feed roll *b'*. Gears *b*² fixed to shafts *b*³, *b*⁴, respectively, drive the upper feed roll *b* from shaft *b*⁴. The supporting structure also comprises a pair of standards *d*, *d'*, which are respectively connected to frame-sides *c*, *c'* by tubular frame members *d*², *d*³. A shaft *e* extends through and is journaled in, frame-sides *c*, *c'* and a shaft *e'* extends through and is journaled in standards *d*, *d'*. A pair of sprocket wheels *e*³ are fixed to each of the shafts *e*, *e'* and a table or platform *f* for supporting the pile of sheets is carried by bars *f'* carried by sprocket-chains *e*⁴ which are operable by said sprockets to raise and lower the table to keep the top of the stack of sheets in predetermined relation to the feed-mechanism which is disposed above the table. Chains *e*⁴ are synchronously driven by gear *g* which is fixed to shaft *e*, a gear *e*⁵ meshing with gear *g*, a sprocket-wheel *e*⁷ rotatable with gear *e*⁵, a sprocket-chain *e*⁸ driven by sprocket *e*⁷ and a similar sprocket on the shaft *e*¹ of sprocket *e*³.

Shaft *e* is driven to elevate table *f* by a pinion *h* which is fixed to a cross-shaft *l* and meshes with a gear *g* which is fixed to one end of shaft *e*. A removable hand-crank *l*² (Fig. 4) is fixed to the end of shaft *l* at the outside of frame-side *c'* for manual rotation of shaft *l* to drive pinion *h* and gear *g* and shaft *e* to raise or lower the sheet-supporting table *f* to position the topmost sheet of the stack into desired vertical relation with respect to the feed-mechanism.

The mechanism for lifting the sheets singly from the stack on table *f* into the bite of the feed rolls *b*, *b'* is mounted on, and carried by, a rectangular frame composed of transverse bars *19* and *80* rigidly connected at their opposite ends by side-members *75* and *76*. Frame bars *81*, which are transversely spaced apart near the transverse center of the machine, are secured to frame-members *19*, *80*, to form guides for the sides of the lifting-shoe frame hereinafter described. This frame carries the pneumatic devices of the sheet-feeding mechanism and is slidably adjustable on tubular frame members *d*², *d*³ to position the pneumatic devices for acting upon the rear ends of sheets, of different lengths, the front ends of which lie at a vertical stationary wall *138*. Side members *75*, *76* are provided with, forked

supporting legs which straddle tubular frame members d^3 , d^2 . A cap plate 77 provided with screws 78 is secured to the lower end of frame side 76 to hold the frame for the pneumatic devices against upward movement relatively to tube d^3 (Fig. 2). Screws 78 threaded to cap 77 , adjustably secure the pneumatic device-carrying frame to tubular member d^2 . Longitudinal adjustment of frame 75 , 76 , 79 , 80 is provided to permit all the devices carried thereby to be set into different positions for acting upon sheets of different lengths. One feature of the present invention is to have the lifting devices act upon the trailing end-portions of the sheets and this adjustment permits said devices to be adjusted for acting upon the trailing ends of sheets of different lengths.

A control finger 121 is positioned to engage the top of the stack of sheets. Mechanism for shifting finger 121 into and out of engagement with the top sheet of the stack to alternately hold and release the sheets comprises a shaft 120 to which finger 121 is fixed and which is journaled in bearings 123 carried by frame-bar 80 ; an arm 127 fixed to shaft 120 ; a connecting rod 24 , one end of which is pivotally and adjustably connected to arm 127 ; an arm 14 pivotally supported on shaft 11 ; and a cam 38 fixed to and driven by a cross-shaft 37 and adapted to engage an abutment roller 22 mounted on arm 14 . Arm 14 is adapted to oscillate finger 121 to cause it to alternately engage and release the top sheet of the stack on table f . Shaft 37 , which operates cam 38 , is driven by suitable gearing from the press so it will revolve once for each printing operation or revolution of the press cylinder. A spring 23 is applied to retract arm 14 toward cam 38 . Arm 14 is also adapted to raise the sheet-supporting table f by means of a pawl 16 which is pivoted to said arm and is adapted to engage and intermittently rotate a ratchet-wheel 15 which is on shaft 11 between arm 14 and pinion 13 . Ratchet 15 is fixed to pinion 13 which meshes with gear 9 on shaft e which, through sprockets e^3 and chains e^4 is adapted to raise the table f . A spring-pressed dog 26 , pivoted at 27 , prevents backward rotation of ratchet 15 . The length of the retractile strokes of arm 14 are controlled and are variable by the downward pivotal movement of finger 121 so that the table f will not be lifted unless the height of the pile has been lowered sufficiently to make it necessary to lift table f and so that the table-lifting mechanism will be lifted responsively and accordingly to the thickness of the sheets to maintain the desired operative relation between the top of the stack and the feed-mechanism. For this purpose, pawl 16 is provided with a notch which, when the pawl is lifted by a tooth on ratchet-wheel 15 during the retraction of the pawl, will be engaged by a tooth 19 on a latch 20 which is pivotally supported at 21 on and oscillates with arm 14 . Latch 20 will then hold pawl 16 disengaged from wheel 15 . While the top of the stack is within proper range of the lifting-mechanism, finger 121 will shorten the retractile stroke of arm 14 and when the top of the stack is lowered by the successive feeding of the sheets therefrom to require lifting of the stack, finger 121 will swing downwardly sufficiently to permit a longer stroke of arm 14 . A latch-controlling arm 35 is fixed to shaft 29 to trip latch 20 . When finger 121 permits a sufficient retractile stroke of arm 14 , the upper end of arm 35 will engage latch 20 to release pawl 16 and permit it to drop into engagement with ratchet 15 to operate the lifting mechanism for table f . As a result, finger 121 controls the operation of the arm 14 to operate the table-lifting mechanism, from the height of the stack and as necessary to maintain operative relationship or spacing between the stack and the feed-mechanism.

Arm 35 is fixed to one end of a cross-shaft 29 and an arm 30 is keyed to the opposite end of shaft 29 . A stop-screw 32 is threaded to a lug 33 on frame side c^1 , and a spring 34 normally holds arm 30 against stop screw 32 . A lock-nut 36 is provided for screw 32 . By adjusting screw 32 contact arm 35 can be set to vary the operation of the table f by arm 14 to maintain the height of the stack substantially at a constant level for reliable feeding of successive sheets of different materials or thickness.

The mechanism for lifting sheets consecutively from the stack on table f comprises a vertically reciprocable shoe or suction plate 112 which is provided with inlet ports 114 , under which pass the perforated belts 57 , the suction being operative on the topmost sheet of the stack through the perforations 58 in said belts. The suction-shoe 112 is integrally formed with a frame 110 which is mounted to slide vertically between frame-members 79 , 80 and frame-bars 81 . Two guide-rollers 116 are carried by the shoe 112 at the rear thereof and two guide-rollers 116^a are carried at the front of said shoe. These rollers guide and deflect a portion of the lower reaches of belts 57 to insure the engagement of their upper faces with the bottom face of shoe 112 and raise and lower said reaches with the shoe. The bottom of the shoe is provided with a pair of inlet ports 114 adjacent its rear which communicates with a cross-port 115 and a similar pair of ports 114 communicate with a cross-port 115 at the front of the shoe 112 . Each port 115 is connected by a flexible pipe 87 to the tube 85 which is journaled in frame-members 76 and 81 . The outer end of pipe 85 is connected to a T-fitting 88 which is connected to the suction side of an air-pump. An adjustable valve 89 is provided on the top of fitting 88 to regulate the degree of suction applied to the pipe 88 and the ports in the shoe 112 . The inner end of pipe 85 is closed.

The mechanism for vertically reciprocating frame 110 to raise and lower suction-shoe 112 into and out of engagement with the topmost sheet comprises a pinion 82 fixed to pipe 85 and meshing with gear-teeth on the inner face of one side of frame 110 , a gear 83 rotatably mounted on a pipe 86 and meshing with gear 83 and gear-teeth on the inner face of the opposite side of frame 110 , an arm 90 fixed to pipe 85 , a rod 41 having one of its ends adjustably and pivotally connected to arm 90 , and a crank 39 to which rod 41 is pivotally connected. Crank 39 is fixed to rotate with the driven shaft 37 and is driven one revolution for each sheet-feeding operation. Shaft 37 is driven by a pinion 48 fixed to shaft b^4 and a gear 46 fixed to shaft 37 . This mechanism raises and lowers the pneumatic shoe 112 and frame 110 to intermittently bring the belts 57 into contact with the topmost sheet so that the latter will be subjected to suction through perforations 58 in said belts from ports 114 and 115 in the shoe.

The means for successively advancing the sheets lifted off the stack on table f comprises a pair of perforated belts 57 , a pair of drive-

wheels 56 for said belts, a cross-shaft 52 to which wheels 56 are fixed, a pair of idler wheels 59 for belts 57 and a shaft 60 on which pulleys 59 are supported. Shaft 60 is supported in the upper end of an arm 61 which is pivotally supported on tubular cross-member 62. A counterweight 65 is adjustably connected to arm 61 to shift shaft 60 and pulleys 59 to keep the perforated belts 57 taut and permit vertical movement of the lower reaches of the belts with shoe 112. The lower reaches of belts 57 contact the uppermost sheet of the stack and are operated intermittently after the shoe has been lifted to successively advance the sheets into the bite of rolls b, b¹ by mechanism operated from shaft 37 which drives cam 38 and is operated one revolution for each feeding operation. This mechanism comprises a crank 43 fixed to one end of shaft 37, a link 45 pivoted to crank 43, a collar 47 held on and rotatably mounted on shaft 52 of belt-pulleys 56, a pawl 49 pivoted to collar 47 and a ratchet-wheel 53 fixed to shaft 52. A dog 54 pivoted to frame-side c¹ prevents reverse rotation of ratchet-wheel 53 and shaft 52. During each operation of the press cylinder, an operative stroke in timed relation to the lifting mechanism will be imparted to belts 57 to advance the lifted sheet held by suction in shoe 112 over a guide 139 and into the bite of rolls b, b¹ in timed relation with the press, as well understood in the art. The feed means comprises a pair of blast-delivery pipes or nozzles 133 for fluffing the side edges of the sheets; and a pipe or nozzle 117 for fluffing or blowing apart the rear edges of the uppermost sheets. Longitudinal adjustment of frame 75, 76, 79 and 80 on tubular members d², d³ makes it possible to position guides 136 and blast-nozzle 117 for acting upon sheets of different dimensions. Air under pressure from the pressure side of a pump is delivered through a pipe 96 into a casing 95. Said casing is connected to and supported by pipe 86 which is fixedly supported in frame-member 76 and one of the frame-bars 81. Flexible pipes 97 connect nozzles 133 to the chamber in casing 95 to deliver air under pressure to said nozzles.

A pair of blast-nozzles 133 are mounted in brackets 131 which are adjustably mounted and transversely adjustable on frame-bar 79. The lower ends of these nozzles are turned inwardly toward the side-edges of the uppermost sheets of the stack on table f and are adapted to fluff the adjacent marginal portions of the uppermost sheets on the stack when blasts of air are discharged from the nozzles. Paper-guides 134 are secured on brackets 131 so that the nozzles 133 and said guides are transversely adjustable for different widths of sheets.

A nozzle 117 is adjustably supported on the frame-bar 80 and its lower end extends forwardly to deliver a blast of air longitudinally under the lifted sheet from its rear edge to its front edge to elevate the portion of the sheet forwardly of shoe 112 with the suction-lifted trailing portion of the sheet.

Valve-means is provided for controlling the blasts from nozzles 133, 117, to alternately deliver the blasts of air to said nozzles. Air under pressure from the pressure side of a pump is delivered through a pipe 96 into a casing 95 which is connected to, and supported by, pipe 86, which is fixedly supported in frame-member 76 and one of the frame-bars 81. Flexible pipes 97 connect nozzles 133 to the chamber in valve-casing 95 to deliver air under pressure to said nozzles. A

flexible pipe 94 is connected to deliver air from pipe 86 to nozzle 117. A valve 98 is pivotally supported in casing 95 and is adapted to alternately cut off the supply of air to pipe 86, pipe 94 and nozzle 117 while air is delivered through pipes 97 to nozzles 133 and to deflect the supply of air from nozzles 133 while permitting it to pass through pipes 86, 94 to nozzle 117. This valve is operated in timed relation with the feed mechanism by an arm 125 fixed to shaft 120 which carries the height-limiting finger 121 and is operated by arm 14. Arm 125 rocks an arm 99 on the pivot-shaft of valve 98.

In setting up the machine for a run, a stack of sheets is placed on table f with the front of the stack adjacent guide-wall 138. The feed-mechanism frame is then adjusted along frame-members d², d³, so that shoe 112 will be disposed over the rear of the stack and guides 136 and nozzle 117 will be located at the rear edge of the stack. The feed-mechanism frame will then be locked in position by screws 18. The adjustable connections between rod 41 and arm 90 and between rod 24 and arm 127 permit this adjustment without variation in the timing of the operation of the suction-shoe lifting mechanism and the mechanism for operating valve 98. Upon moving lever arms 90, 127 to a position in line with setting-up locations indicated on the side of frame member 76, thumb-screws 93, 130 will be tightened to render said rods operative in their adjusted positions. Brackets 131 will be adjusted transversely to position side-guides 134 at the sides of the stack and to position nozzles 133 to deliver blasts to the sides of the upper sheets of the stack. Screw 32 may be adjusted to alter the height of the top of the pile relative to shoe 112. The air-blast nozzles 117, 133 will be adjusted vertically to deliver blasts at the desired level. The air-pump will then be operated continuously to supply air under pressure to casing 95 and apply suction to the fitting 88. Nozzles 133 are set to fluff and raise the top several sheets of the stack approximately $\frac{1}{4}$ inch and the blast of air is sufficient for that purpose. Screw 32 is adjusted to maintain the top of the stack of sheets in desired relation to the feed-mechanism according to the thickness or character of the sheets. Crank-arm 39 on cam-shaft 37 can be revolved to a position where suction-shoe 112 and belts 57 against its bottom face will be lowered into the fluffed portion of the sheets.

In operation, crank-arm 39 in properly timed relation to the press, will revolve and lower suction-shoe 112 with belts 57 against its bottom face, onto the sheets which will be fluffed by blasts of air from nozzles 133. During downward travel of shoe 112, cam 38 raises control-finger 121 from the contact it has last made with the top sheet of the stack and valve 98 cuts off air to nozzle 117 and permits air to flow to nozzles 133. During the lower portion of this downward movement of shoe 112 and belts 57, crank-arm 43 is revolving on its idle stroke so that belts 57 are not advanced. Idler pulleys 59 hold the belts 57 taut to permit the vertical movement of the lower reaches of said belts with shoe 112. Suction is constantly applied through perforations 58 in the belt and inlets 114 in the shoe so that the top sheet, when the shoe 112 is lowered, will adhere to the belts and be lifted upwardly therewith. When arm 39, in its rotation, has lifted shoe 112 and belts 57 sufficiently to raise the sheet just above level of the blast from nozzle 117, cam 38 will rock arm 125 to lift lever 99 and shift valve

98 to deflect the blast from nozzles 133 and direct a stream of air momentarily through nozzle 117 for a strong quick blast directed forwardly under the lifted sheet. This blast of air will raise the entire central area of the lifted sheet into clinging contact with the entire forward length of the lower reaches of belts 57 (Fig. 3). The sheet is thus lifted above guide 139 and advanced to rollers b, b¹ under power derived from crank 43 which, at this moment, is positioned where arm 45 is operating collar 47 and pawl 49 and advancing ratchet-wheel 53 to turn shaft 52 and drive pulleys 56 and belts 57. At this time the cam 38 has revolved to such an extent that control-finger 121 will be lowered sufficiently to prevent any possible displacement of the position of the several top sheets by the feeding action of belts 57. As the lower reaches of belts 57 advance over ports 114, suction is first applied to the sheet from successive holes 58. When the trailing end of the sheet passes beyond the range of the rear pair of holes 114, air enters said holes. By reason of the arrangement described with respect to tubes 87, such entry of air does not interfere with the sufficiency of the front air holes 114 to continue to hold the sheet until its feed is completed and the trailing end of the sheet passes beyond range of the shoe 112. During this advancing action, cam 38 is revolved to permit arm 14 to swing toward the low portion of cam 38 and if sufficient sheets have been fed from the pile, control finger 121 will drop sufficiently to release pawl 16 for engagement with ratchet 15 and, upon further rotation, the high surface of cam 38 will cause shaft e to rotate and raise table f and the stack of sheets thereon. The elements of the feed-mechanism are timed and co-ordinated so that nozzles 133 will fluff the uppermost sheets of the stack while the suction-shoe 112 and frame 110 are being lowered to cause belts 57 to engage the uppermost sheet. During this period, the air entering the suction-shoe 112 will pass to the suction side of the air-pump so that the blast from the pressure side will be sufficiently high in pressure to cause the air from nozzles 133 to fluff the sheets at their sides. When belts 57 and the suction-shoe 112 are lowered so that the topmost sheet closes the perforations 58 in the belts, the pressure of the air from the pump will be automatically reduced to cause the sheets below the one held by the belts to drop away therefrom. During the up-stroke of shoe 112 and belts 57 with the sheet held thereby, valve 98 will be operated to deflect the remaining blast from nozzles 133 and deliver a blast through nozzle 117 at the rear of the sheet. This blast will pass under the suspended sheet and cause the front portion of the sheet to be lifted with the shoe. The nozzles 133 are disposed to separate or fluff only the rear portion of the sheets so that during the engagement of height-control finger 121 with the top sheet of the stack, the front portion of the sheets may remain together. The timed blast from the nozzle 117 causes the portion of the sheet ahead of the shoe 112 to be separated from the stack as the shoe is raised preparatory to the advance of the sheet by the intermittent operations of belts 57 which will deliver the front edge of the sheet to the rollers b, b¹.

The invention exemplifies suction-controlled lifting means, such as shoe 112, which is movable in a vertical path to separate the uppermost sheet from the stack and means, such as perforated belts, for advancing the lifted sheets to

the press. The invention also exemplifies feeding-mechanism which operates on the trailing ends of the sheets to successively separate them from the stack and advance them to the press. 5 The invention also exemplifies lifting mechanism and associated pneumatic means for fluffing the sides of the sheets to aid in the separation of the uppermost sheet from the remainder of the stack. The invention also exemplifies means for delivering 10 a blast of air from the rear to the front of the sheets to separate the uppermost sheet from the remainder of the stack during the lifting and advancing of the uppermost sheet. The invention also exemplifies feed mechanism which is 15 readily adjustable for sheets of different sizes and efficient and rapid in operation.

The invention is not to be understood as restricted to the details set forth, since these may be modified within the scope of the appended 20 claims, without departing from the spirit and scope of the invention.

Having thus described the invention, what I claim as new and desire to secure by Letters Patent is:

25 1. In sheet feeding mechanism for printing presses and the like, the combination of means for supporting a stack of sheets, vertically movable suction-means for successively lifting the sheets vertically from the stack, and intermittent 30 means for successively advancing the sheets horizontally beyond the suction-means, said intermittent means comprising a part movable vertically with the suction-means.

2. In sheet feeding mechanism for printing 35 presses and the like, the combination of means for supporting a stack of sheets, vertically movable suction-means for successively lifting the sheets vertically from the stack, and intermittent means for successively advancing the sheets 40 horizontally relatively to, and while they are held by, and beyond the suction-means, said intermittent means comprising a part movable vertically with the suction-means.

3. In sheet feeding mechanism for printing 45 presses and the like, the combination of means for supporting a stack of sheets, a vertically movable suction-shoe for intermittently and successively lifting the sheets from the stack, and means for successively advancing the sheets horizontally past and while held by the shoe comprising a part movable vertically with the suction-means.

4. In sheet feeding mechanism for printing 55 presses and the like, the combination of means for supporting a stack of sheets, vertically movable sheet-lifting means engageable only with the trailing portions of the sheets, and means for consecutively advancing the lifted sheets comprising a part movable vertically with the lifting-means.

60 5. In sheet feeding mechanism for printing presses and the like, the combination of means for supporting a stack of sheets, vertically movable suction-operable sheet-lifting means engageable only with the trailing portions of the sheets, and means for consecutively advancing the lifted sheets comprising an endless belt having a portion thereof movable vertically of the lifting-means.

6. In sheet feeding mechanism for printing 70 presses and the like, the combination of means for supporting a stack of sheets, vertically movable sheet-lifting means engageable only with the trailing portions of the sheets, means for consecutively advancing the lifted sheets, comprising a belt having a portion thereof movable with

the lifting-means and means for delivering a blast of air under the sheets to lift the front portions of the sheet while they are being advanced.

7. In sheet feeding mechanism for printing presses and the like, the combination of means for supporting a stack of sheets, means for lifting and advancing sheets from the stack, and means for alternately delivering a blast of air to one of the side-edges of the sheets and delivering a blast to the trailing edges of the sheets.

8. In sheet feeding mechanism for printing presses and the like, the combination of means for supporting a stack of sheets, suction-operable lifting means for the sheets, an endless perforated belt for advancing the lifted sheets, a portion of said belt being movable vertically by the lifting means, and mechanism for intermittently operating the lifting means and the belt to successively lift and advance the sheets consecutively from the stack.

9. In sheet feeding mechanism for printing presses and the like, the combination of means for supporting a stack of sheets, a suction-shoe for lifting the sheets provided with inlets in advance of one another, an endless perforated belt for advancing the lifted sheets, a portion of said belt being movable vertically by the shoe, and mechanism for intermittently lifting the shoe and operating the belt to successively lift and advance the sheets consecutively from the stack.

10. In sheet feeding mechanism for printing presses and the like, the combination of means for supporting a stack of sheets, lifting means comprising a longitudinally adjustable frame, a suction-shoe vertically slidable in the frame and mechanism for raising and lowering the shoe in said frame, an endless perforated belt extending under the shoe, means for guiding the belt across the lower face of the shoe, and means for intermittently operating the belt to advance the sheets while lifted by the suction-shoe.

11. In sheet feeding mechanism for printing presses and the like, the combination of means for supporting a stack of sheets, lifting means comprising a frame, a suction-shoe slidable vertically in the frame and provided with inlets in advance of one another, mechanism for raising and lowering the shoe in said frame comprising a rotatable pipe connected to deliver air to the shoe, an endless perforated belt extending under the shoe, means for guiding the belt across the lower face of the shoe, and means for intermittently operating the belt to advance the sheets while held by the suction-shoe.

12. In sheet feeding mechanism for printing presses and the like, the combination of means for supporting a stack of sheets, lifting means comprising a frame, a suction-shoe slidable vertically in the frame and provided with inlets in advance of one another, mechanism for raising and lowering the shoe in said frame comprising a rotatable pipe connected to deliver air to the shoe and a pair of gears operable by said pipe, an endless perforated belt extending under the shoe, means for guiding the belt across the lower face of the shoe, and means for intermittently operating the belt to advance the sheets while held by the suction-shoe.

13. In sheet feeding mechanism for printing presses and the like, the combination of means for supporting a stack of sheets, lifting means comprising a longitudinally adjustable frame, a suction-shoe slidably mounted in the frame, mechanism for raising and lowering the shoe in said frame, endless perforated belts extending

under the shoe, means for guiding the belts across the lower face of the shoe, means for intermittently operating the belts to advance the sheets while held by the suction-shoe, and means mounted on said frame for delivering blasts of air to the edges of the sheet.

14. In sheet-feeding mechanism for printing presses and the like, the combination of a rectilinearly and vertically movable suction-shoe for shifting sheets vertically from a level-controlled pile, and an intermittently operated endless belt for successively advancing the sheets horizontally, having a portion thereof guided across the shoe and movable vertically therewith.

15. In sheet-feeding mechanism for printing presses and the like, the combination of means for supporting a stack of sheets, means for intermittently engaging and lifting a transversely central portion of the top sheet, means for delivering a transverse blast of air to one side-edge of the sheets laterally of the lifting means for separating the side portion of the sheets and co-acting with the lifting means in separating the top sheet, and means for intermittently advancing the lifted sheet.

16. In sheet-feeding mechanism for printing presses and the like, the combination of means for supporting a stack of sheets, vertically movable suction means for intermittently engaging and lifting the transversely central portion of the top sheet, means movable vertically with the suction means for delivering a transverse blast of air to one side-edge of the sheets laterally of the lifting means for separating the side portion of the sheets and co-acting with the lifting means in separating the top sheet, and means for intermittently advancing the lifted sheet.

17. In sheet-feeding mechanism for printing presses and the like, the combination of means for supporting a stack of sheets, vertically movable suction means for intermittently engaging and lifting the transversely central portion of the top sheet, means movable vertically with the suction means for delivering a transverse blast of air to each of the side-edges of the sheets laterally of the lifting means for separating the side portion of the sheets and co-acting with the lifting means in separating the top sheet, and means for intermittently advancing the lifted sheet.

18. In sheet-feeding mechanism for printing presses and the like, the combination of means for supporting a stack of sheets, means for intermittently engaging and lifting the transversely central portion of the top sheet, means for delivering a transverse blast of air to each of the side-edges of the sheets toward the lifting means for separating the side portion of the sheets and co-acting with the lifting means in separating the top sheet, and means for intermittently advancing the lifted sheet.

19. In sheet-feeding mechanism for printing presses and the like, the combination of means for supporting a stack of sheets, means for intermittently engaging and lifting the transversely central portion of the top sheet, means for delivering a transverse blast of air to each of the side-edges of the sheets toward the lifting means for separating the side portion of the sheets and co-acting with the lifting means in separating the top sheet, means for delivering a blast to the trailing edge of the sheets after the lifting means has engaged the sheet, and means for intermittently advancing the lifted sheet.

20. In sheet-feeding mechanism for printing presses and the like, the combination of means for supporting a stack of sheets, a suction-shoe for intermittently engaging and lifting the transversely central portion of the top sheet, means for delivering a transverse blast of air to each side-edge of the sheets laterally of and

in advance of the engagement of the shoe for separating the side portion of the sheets and assisting the lifting means in separating the top sheet, and means for intermittently advancing the lifted sheet.

BRUCE WALE.
